(57) **CLAIM**

The ornamental design for a shelf organizer, as shown and described.

DESCRIPTION

FIG. 1 is a perspective view of a shelf organizer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof with one of shelves being removed; and,

FIG. 9 is an enlarged view of an indicated portion of FIG. 1.

The broken line portions of the shelf organizer in FIGS. 1-9 represent unclaimed portions of the claimed design and form no part thereof.

1 Claim, 8 Drawing Sheets
